L. C. TABER, OF EATON, NEW YORK.

Letters Patent No. 87,221, dated February 23, 1869.

IMPROVEMENT IN DAMPERS.

The Schedule referred to in these Letters Patent and making part of the same.

To all whom it may concern:

Be it known that I, L. C. TABER, of Eaton, in the county of Madison, and State of New York, have invented a new and useful Improvement in Stove-Dampers; and I do hereby declare that the following is a full and exact description thereof, reference being had to the accompanying drawings, making a part of this specification—

Figure 1 being a perspective view.

Figure 2, a vertical section.

Figure 3 is a bottom view of the expansion-rod and nut.

Figure 4 is a side view of the lever.

The nature of my invention consists in applying to a stove, or stove-pipe, a damper which will open itself when there is more fire than is required, and which will close itself when there is less fire than is required, admitting air to the flue or pipe when open, thereby checking the draught through the fire, and when closed, causing the draught to pass through the fire.

To enable others skilled in the art to make and use my invention, I will proceed to describe its construction and operation.

I construct my improved damper as follows, viz:

I apply, to the back boiler-hole of a cook-stove, a rim, A.

B is a cover supported upon its pins. One side of said cover is enough heavier than the other, to open it, as shown in the drawings, figs. 1 and 2.

Under the heavy side of said cover, I apply the long arm of lever E, and to the short arm of said lever, I apply a brass rod, F, partly encircling the rim A. One end of said rod is secured permanently to rim A at G.

To the opposite end of rod F, I apply a nut, H, for the purpose of tightening or loosening said rod, by means of which the damper or cover may be so set, or adjusted, as to admit any desired amount of air.

When the action of the damper is not needed, it may be fastened by means of the button i.

By the foregoing description it will be seen that my improved damper is only applicable to a stove back of the fire.

The damper-lid will open by its own gravity when uncontrolled, but by the united action of the lever and the brass rod, it is held closed, or partially closed, as adjusted by the thumb-screw, except when said rod is expanded by heat.

In Figure 5 my improved damper is shown as applied to the boiler-hole of a stove.

In Figure 6 it is applied to an opening, cut for the purpose, in the stove-pipe. It may in like manner be applied to any part of the smoke-flue.

Having thus fully described my invention,

What I claim, and desire to secure by Letters Patent, is—

The employment of a self-adjusting stove-damper, substantially as and for the purposes set forth.

The above specification of my improved stove-damper, signed and witnessed, this, the 28th day of November, 1868.

L. C. TABER.
